MACHINE FOR MAKING T'S OF METAL TUBING

John Q. Holmes and Basil S. Sample, Anderson,
Ind., assignors to General Motors Corporation,
Detroit, Mich., a corporation of Delaware

Application April 14, 1941, Serial No. 388,396

9 Claims. (Cl. 153—2)

This invention relates to the art of fabricating metal tubing into articles such as manifolds for delivering lubricating oil to the crank shaft bearings of an internal combustion engine. The patent of Nichols and Weiser No. 2,297,013, issued Sept. 29, 1942, discloses a method by which a section of metal tubing can be provided with a side opening and socket, the inside diameter of which is equal to the outside diameter of the tube. This socket receives another section of tubing of the same outside diameter as the first section in order to provide a T. One section of the tubing conducts liquid to the other section which may be provided with branches of smaller diameter spaced so as to distribute oil properly to the crank shaft bearings of an engine.

It is an object of the present invention to provide a machine by which the operations disclosed in the Nichols and Weiser application can be economically carried out.

Further objects and advantages of the present invention will be apparent from the following description, reference being had to the accompanying drawings wherein a preferred embodiment of the present invention is clearly shown.

In the drawings:

Fig. 1 is an end view of the machine embodying the present invention.

Fig. 2 is a plan view partly in section, the section being taken on the line 2—2 of Fig. 1 and certain parts being omitted for the sake of clearness.

Fig. 3 is a fragmentary sectional view on the line 3—3 of Fig. 2 and is drawn twice the scale of Fig. 2.

Figs. 4, 5 and 6 show the three operations which are successfully performed upon a fragment of tubing by the tools shown best in Fig. 3.

Figs. 7 and 8 taken together constitute a sectional view on line 7—7 of Fig. 3.

Fig. 9 is a fragmentary sectional view on line 9—9 of Fig. 2.

Fig. 10 is a diagram of a compressed air system including control valves and air cylinders for operating the tools which perform the operations indicated in Figs. 4, 5 and 6.

Referring to sections 1, 2, 7 and 8 the machine comprises a base 20 providing an opening 21 for the discharge of the completed work and supporting bearing brackets 22 and 23 upon which a shaft 24 is journaled, said bearings being completed by bearing bracket caps 22a and 23a secured by screws to the brackets 22 and 23. The shaft 24 supports spiders 25, 26 and 27 providing cylindrical surfaces 25a, 26a and 27a to which are

secured sheet metal sleeves 28 stiffened by bars 29 attached by screws 30. The spiders 25, 26 and 27 are provided respectively with eight flat surfaces 25b, 26b and 27b. Each of the flats 25b supports a block 31 provided with notch 32 for receiving the flattened end 33 of a tube T. The other end of the tube T rests upon a groove block 34 there being eight of these blocks attached respectively to the eight flats 27b of spider 27. Intermediate its ends, the tube T is supported by a grooved block 35 having a central socket 36 (Fig. 2), for the purpose of receiving portions of the tube which are enlarged during the third operation performed by the machine. The tube T is clamped in the required position upon its workholder by a lever 40 having a socket 41 for receiving the round end of the tube as shown in Fig. 8. Lever 40 is pivoted upon a pin 42 supported by a pair of ears 43 integral with spider 27. A spring 44 confined in a socket 45 of spider 27 urges the lever 40 counterclockwise (Fig. 8). The right end of spring 44 is retained by a pin 46 in lever 40. Lever 40 is provided with a handle 47 against which the operator presses to move the lever 40 clockwise when he places the tube T in position.

By a ratchet mechanism to be described, the shaft 24 is rotated intermittently clockwise as viewed in Figs. 1 and 3 to carry the work into the work stations A, B and C (Fig. 3) and finally into a discharge station D. At station D the work retaining lever 40 is moved into the position 40' (Fig. 8) so that the work may gravitate from the workholder and move down a chute into a suitable receptacle not shown. As a lever 40 approaches station D its stud 46 is engaged by a cam 50 carried by a plate 51 secured to a plate 52 fixed to bracket 23.

A ratchet 60 having pawl receiving notches 61 is secured to shaft 24 by pin 62. Shaft portion 24a (Fig. 8) provides a journal for a bearing 63 for a collar providing a hub 64 welded to a plate 65 providing a ratchet carrier. Parts 64 and 65 are retained by a disc 66 attached by a screw 67 to shaft 24. Plate 65 supports a screw stud 68 secured by nut 68a providing a pivot for a pawl 69 for successively engaging the notches 61 of ratchet 60. These notches are successively engaged also by a locating pawl 70 journaled on a screw 71 fixed to bracket 23. Pawl 70 is urged counterclockwise (Fig. 1) about its pivot 71 by a rod 72 guided by a bracket 73 housing a spring 74 for urging the pawl 70 upwardly. When the plate 65 is moved counterclockwise (Fig. 1) by mechanism to be described to cause pawl 69 to

move to the left to engage a notch 61', a cam plate 75 attached by screws 76 to plate 65 will engage a roller 77 pivotally supported by pawl 70 thereby causing pawl 70 to be disengaged from the ratchet 60. When the plate 65 is moved clockwise the pawl 69 will move the ratchet 60 through 45°; and the ratchet notch 61'' (Fig. 1) will have been brought into alignment with the pawl 70 which, upon completion of clockwise movement of plate 65 through 45°, will be forced by rod 72 into engagement with the ratchet in order to lock the work-holder in a new work position.

The plate 65 is oscillated by a mechanism comprising an air cylinder 80 cooperating with a piston, not shown, which is connected with a piston rod 81 connected by a pin 82 with a block 83 attached to a slide 84 guided in ways 85 provided by a bracket 86 (Figs. 3 and 9). The right end of slide 84 (Fig. 9) is attached by pivot screw 87 to a link 88 having a slot 89 for receiving a pivot screw 90 on an arm of a bell crank lever 91 pivoted on a screw 92 fixed to a bracket 93 attached to base 20. The other arm of lever 91 is connected with rod 94 by a ball and socket connection at 95. The other end of rod 94 is connected by a ball and socket connection 96 with plate 65. When air is admitted to the head end of cylinder 80 the rod 81 moves downwardly (Fig. 2) or toward the right (Fig. 9) in order to effect counterclockwise movement of plate 65 in order to back the ratchet-moving pawl 69 and to retract the ratchet-locating pawl 70. When air is admitted to the piston rod end of cylinder 80 the plate 65 is moved clockwise in order that the workholder may be indexed 45° and then be located by the pawl 70. The slot in the end of link 88 provides a lost motion connection between the operating piston rod 81 and the pawl carrier 65. This lost motion is required because the piston rod 81 is connected with another mechanism to be described, said mechanism requiring greater movement than is required by the indexing mechanism.

Referring to Figs. 3, 7 and 8 a bracket 100 mounted upon the base 20 is provided with three mounting pads 101, 102 and 103 which are machined surfaces located at 45° with respect to each other. Surface 101 supports cylinder 104 containing a piston, not shown, connected with a piston rod 105. Rod 105 is threadedly engaged by a screw having a knurled head 106 and a shank 107 terminating in a plain cylindrical head 108 received in a socket 109 provided by the co-operation of a tool supporting base 110 and an annular ring 111 secured by screws 112 and having an integral flange 113 engageable with the head 108 of screw 106. By turning the knurled part 106, the distance between the piston rod 105 and the tool supporting base 110 can be adjusted. Base 110 is provided with bushings 115 (Figs. 7 and 8) for receiving stationary pilot pins or rods 116 fixed to the mounting pad 101 of frame 100. The rods 116 guide the workholder base 110 during movement thereof by the piston rod 105. To the base 110 is secured a block 120 by screws 121. Block 120 guides a pressure block 122 having notches 123 for receiving the tube T when the block 122 has been moved into engagement with the block 35 adjacent thereto. The pressure block 122 is prevented from turning with respect to the block 120 by a key 124 fixed to the block 120 and received by a notch in the flange 125 of block 122. The block 120 retains a plate 126 to which is fixed the upper end of a punch 127

for performing the operation upon the tubing while at station A. A spring 128 confined between a shoulder 129 of block 122 and the plate 126 urges block 122 downwardly until its flange 125 engages a shoulder 125a of block 120. When air under pressure is admitted to the head end of cylinder 104 through opening 104a to which a pipe is attached, rod 105 moves downwardly to cause pressure block 122 to engage tubing T and to force the same against block 35 while at station A and to hold said block 122 against the work under yielding pressure afforded by spring 128 while the tool 127 so changes the tube T that a rectangular hole 11 (Fig. 4) is changed into a circular hole 12 bounded by arcuate flanges 13 which extend outwardly. As disclosed in the patent to Nichols and Weiser #2,297,013, the rectangular hole 11 is formed by a shearing punch which leaves those edges of hole 11 extending lengthwise of the tube T relatively sharp. The curvature of the punch 127 in an axial direction is such that, when the punch 127 engages these sharp edges, they move outwardly, rather than inwardly toward the interior of the tube, because it is easier for the metal of the tube to move in an outward direction rather than to follow down with the punch 127. These edges of hole 11 are relatively thin and are easily bent upward as the punch 127 engages them. The displacement of the rest of the metal surrounding the hole 11 readily follows in an upward and outward direction. Thus the rectangular hole 11 becomes a circular hole 12 bounded by arcuate flanges 12. Following this operation, air is admitted through a pipe connected with the piston rod end of cylinder 104 through the tapped opening 104b to cause the block 122 and tool 127 to be retracted.

Mounting pad 102 supports an air cylinder 130 containing a piston connected with a piston rod 131 which is associated with parts similar to all of the parts which have been described in connection with cylinder 104 with the exception that the tool 132 differs from the tool 127 at station A with respect to its contour. Tool 132 is so shaped as to cause the flanges 13 (Fig. 4) to be spread apart to form the somewhat arcuate flanges 14 (Fig. 5) surrounding a hole 15 of somewhat elliptical shape. As the pressure block 122 at station B is retracted from the work, tube T is prevented from being dislodged from the block 35. For this purpose, there are two bars 135 (Figs. 7 and 8) fixed at their lower ends by screws 136 to bracket 100.

The third operation performed at station C is to shape the opening 15 into a circular opening 16 as shown in Fig. 6 and to cause the side walls of the tube T to be enlarged as indicated at 17 in Figs. 3 and 6, thereby providing a cylindrical socket for receiving a tube whose outside diameter equals the outside diameter of the tube T being operated upon by this machine. The tool 140 (Fig. 3) for performing this operation has an end 141 of oblong cross section adapted to enter the opening 15 of Fig. 5. While the tool 140 is thus entered, it is caused to rotate thereby changing the elliptical hole 15 into the circular hole 16 (Fig. 6). The tool 140 has a shank 142 extending through a hole in a retainer plate 143 fixed to a sleeve 144 by screws 145 which also secure a ring 146 providing a socket 147 for receiving a pressure block 148 having a notched end 149 for receiving the tube T when said block 148 moves toward the work supporting block 35. The tube T is thus held by the block 148 under yielding pressure afforded by springs 150 confined by

sockets 151 provided by ring 143 and sockets 152 provided by block 148. While the tube T is thus clamped between the blocks 148, and 35 at station C under yielding pressure, the tool 140 is positioned into the opening 15 (Fig. 5) and is caused to rotate. To accomplish this the tool 140 is provided with a flanged head 155 having a cross rib 156 entering a groove in the head 151 of a shaft 158 journalled in bearings 159 and 160 supported by the sleeve 144. Sleeve 144 is slidably guided by a bushing 161 and is prevented from rotating relative thereto by a key 162 providing a splined connection between sleeve 144 and bushing 161. Bushing 161 extends through a circular opening 163 in frame 100 and it is provided with an annular flange 164 attached to the mounting pad 103. The shaft 158 is moved axially by moving the sleeve 144 axially. This is accomplished by an air cylinder 170 cooperating with a piston, not shown, connected with a rod 171 connected by a turnbuckle screw 172 with a yoke 173 integral with an annular flange 174 secured by screws 175 to sleeve 144. The turnbuckle 172 is clamped in adjusted position by knurled head lock nuts 176 and 177 (Fig. 2).

The shaft 158 is rotated by movement of the piston rod 81 cooperating with cylinder 80. The slide 84 connected with rod 81 (Fig. 9) operates a rack 180 attached by screws 181 and meshing with a pinion 182 connected with shaft 158 by keys 183 (Fig. 3) and locked by a set screw 184 (Fig. 3).

Referring to Fig. 10, a pipe 200 connects a compressed air source with a valve 201 connected with an inlet pipe 202 leading into a reducing valve assembly included within the dot dash line rectangle 203. The outlet pipe 204 of this assembly is connected with a four-way valve 205 and by a branch pipe 206 with a four-way valve assembly 207. Valve 205 is connected with the head end of cylinder 170 by pipe 208 and with the piston rod end of cylinder 170 by pipes 209 and 210. Valve 205 is connected with the head end of piston 130 by pipes 208 and 211, and with the piston rod end of cylinder 130 by pipe 209. Valve 205 is connected with the head end of cylinder 104 by pipes 208, 211 and 212 and with the piston rod end of cylinder 104 by pipes 209 and 213. Valve 205 is controlled by foot operated pilot valve 215 connected by pipe 216 with pipe 204 and connected with valve 205 by pipe 217. When the foot of the operator is not applied to an operating member (not shown) of valve 215 communication between pipes 216 and 217 is blocked off, thereby permitting a spring (not shown) in valve 205 so to move a movable valve part so that pipe 204 is connected with pipes 209, 210 and 213 so that the piston rod ends of all of the air cylinders 104, 130 and 170 are connected with the air line 200 thereby causing all of the tools at stations A, B and C to be retracted. During this status of valve 205, the head ends of the cylinders are vented through pipes 212, 211, 208, pipe 208 being connected with atmosphere through the valve 205. At this time the valve 207 causes a pipe 220 to be connected with pipe 206 thereby connecting the piston rod end of cylinder 80 with the air line 200. Therefore the piston rod is moved all the way toward the left in Fig. 9 and the indexing mechanism is in the position shown in Fig. 1. The operation of cylinder 80 is controlled by valve 207; and valve 207 is controlled by pilot valves 221 and 222. Valves 207, 221 and 222 are interconnected by pipes 223 and 224 and valve 222 is connected by pipe 225

with pipe 206. When air is being admitted to the piston rod end of cylinder 170 the yoke 173 associated with said piston 170, due to its connection with rod 171, will be in the position shown in Fig. 1. When in this position it causes pilot valve 221 (Figs. 10 and 1) to be opened while valve 222 remains closed. This is accomplished by connecting the yoke 173 by a link 230, an arm 231 and a shaft 232 with a lever 233 carrying an adjustable screw 234 for engaging the operating member of valve 221 to open said valve. When valve 221 is opened, there is no air pressure present in valve 207 to cause its movable valve member, not shown, to move into such position as to connect pipe 206 with the head end of cylinder 80. Therefore a spring maintains this movable valve member in such position as to connect only the pipe 222 with the pipe 206 while the head end of cylinder 80 is being vented through a pipe 228. When air is admitted into the head end of piston 170 to cause tool 140 (Fig. 3) to move toward the left and the yoke 173 (Fig. 1) to move toward the left, the lever 233 will cause a screw 235 carried thereby to engage the operating member of valve 222 to move downwardly in order to open valve 222 while valve 221 is closed by a spring contained within it. Under these conditions air is admitted through pipes 225, valve 222, pipe 223 to a control member of valve 207, thereby causing the movable valve member to move into a position against the action of a spring to connect pipe 206 with pipe 228 and to vent pipe 226. Air being admitted through the head end of cylinder 80, the piston rod 81 will move downwardly in Fig. 2 or to the right in Fig. 9, thereby causing rack 180 to move toward the right and to cause the pinion 182 to rotate counterclockwise in Fig. 9 and to cause the tool 140 to rotate counterclockwise looking in the direction of the arrow 140a of Fig. 3 or to rotate clockwise as indicated by the arrow 140b in Fig. 6. This causes the tool 140 shown in section in Fig. 5 to rotate 180° and then stop. By this time the elliptical opening 15 has been changed into the circular opening 16 and a cylindrical socket has been provided for the reception of another tube of same outside diameter as the tube T. The displaced metal is caused to be shaped into arcuated flanges 18 by camming surfaces 140c provided by tool 140. The operations of the various tools 127 and 132 and 140 are described in detail in the copending application of Nichols and Weiser referred to.

Following the completion of the operations performed at stations A, B and C, the operator releases pressure of the foot upon the operating member of valve 215 and the tools are retracted and the tool 140 is rotated back to normal position. As the result of restoration of the yoke 173 to normal position shown in Fig. 2 which effects the reclosing of valve 221 and the opening of valve 222. During the operation of the machine, all that is required of the operator is to load tubes T at station L, the loading station, upon the workholder block 35 and then depress a pedal control valve 215 to cause the tools 127, 132 and 140 to operate upon the tubes which are located at stations A, B and C respectively. Release of the foot pressure upon the operating member of valve 215 is followed by restoration of the tools from the work and the indexing of the workholder shaft 24 clockwise (Fig. 1) into the next position. The finished work is discharged at discharge station D and gravitates upon a chute to which guides it to a receptacle.

While the embodiment of the present invention as herein disclosed, constitutes a preferred form, it is to be understood that other forms might be adopted, all coming within the scope of the claims which follow.

What is claimed is as follows:

1. A machine for progressively enlarging an opening in the side of a tube comprising, in combination, a conveyor provided with a plurality of workholders each for supporting a tube having an opening previously formed therein, means for intermittently moving the conveyor in order to move the workholders progressively into a plurality of operating stations, devices located respectively at the operating stations for progressively shaping the tube so that the preformed opening becomes a larger circular opening defined by outwardly projecting arcuate flanges, then an elongated opening formed by spreading said arcuate flanges, and finally a still larger circular opening, each of said forming devices including a forming punch, means for actuating said punches toward and away from the tubes and means for rotating the punch at the last operating station while said punch is entered within the tube.

2. In a machine for progressively enlarging an opening in the side of a tube, the combination comprising a work holder for supporting a tube having a previously formed opening of substantially elliptical shape, a forming punch for entering the opening, said punch being rotatable to form the tube so as to provide an opening of circular shape, a shaft connected with the punch, means for moving the shaft axially, means for rotating the shaft, and means responsive to movement of the shaft axially to carry the punch into the tube for causing the shaft rotating means to become effective.

3. In a machine for progressively enlarging an opening in the side of a tube, the combination comprising work holders each for supporting a tube having a previously formed opening of substantially elliptical shape, a forming punch for entering the opening, said punch being rotatable to form the tube so as to provide an opening of circular shape, a conveyor for supporting the workholders and movable intermittently to locate tubes successively adjacent to the punch, means for operating the conveyor and including a reciprocating member and a one-way motion transmitting means between the reciprocating member and conveyor, means for moving the punch axially through the opening in the tube adjacent thereto, and means for rotating the punch while within the tube, said means being operated by the reciprocating member when moving in such direction that the one-way motion transmitting means is non-operative and the conveyor is stationary.

4. In a machine for progressively enlarging an opening in the side of a tube, the combination comprising work holders each for supporting a tube having a previously formed opening of substantially elliptical shape, a forming punch for entering the opening, said punch being rotatable to form the tube so as to provide an opening of circular shape, a conveyor for supporting the work holders and movable intermittently to locate tubes successively adjacent to the punch, means for operating the conveyor and including a reciprocating member and a one-way motion transmitting means between the reciprocating member and conveyor, means for moving the punch axially through the opening in the tube adjacent

thereto, means operated by said reciprocating member for rotating the punch, and apparatus rendered effective in response to the retraction of the punch from the tube for causing said reciprocating member to operate in a direction to cause said one-way motion transmitting mechanism to be effective to move the conveyor, and said apparatus rendered effective in response to entry of the punch within the tube for causing

5 10 15 20 25 30 35 40 45 50 55 60 65 70

said reciprocating member to operate in the opposite direction whereby the conveyor is stationary while the punch is rotated when within the tube.

5. A machine for progressively enlarging an opening in the side of a tube comprising, in combination, a conveyor provided with a plurality of workholders each for supporting a tube having an opening previously formed therein, means for intermittently moving the conveyor in order to move the workholders progressively into a plurality of operating stations, devices located respectively at the operating stations for progressively shaping the tube so that the preformed opening becomes a larger circular opening defined by outwardly projecting arcuate flanges, then an elongated opening formed by spreading said arcuate flanges, and finally a still larger circular opening, each of said forming devices including a forming punch, means for actuating said punches toward and away from the tubes, means for rotating the punch at the last operating station while said punch is entered within the tube and a controller for said punch rotating means rendered effective by the positioning of the punch at the last operating station within the tube to cause the punch rotating means to operate.

6. A machine for progressively enlarging an opening in the side of a tube comprising, in combination, a conveyor provided with a plurality of workholders each for supporting a tube having an opening previously formed therein, means for intermittently moving the conveyor in order to move the workholders progressively into a plurality of operating stations, devices located respectively at the operating stations for progressively shaping the tube so that the preformed opening becomes a larger circular opening defined by outwardly projecting arcuate flanges, then an elongated opening formed by spreading said arcuate flanges, and finally a still larger circular opening, each of said forming devices including a forming punch, means for actuating said punches toward and away from the tubes, means for rotating the punch at the last operating station while said punch is entered within the tube, and a controller for the conveyor moving means rendered effective by the positioning of the punches outside the tube for conditioning the controller for causing the conveyor moving means to operate.

7. A machine for progressively enlarging an opening in the side of a tube comprising, in combination, a conveyor provided with a plurality of workholders each for supporting a tube having an opening previously formed therein, said conveyor being movable intermittently to carry the tubes progressively into a plurality of operating stations, devices located respectively at the operating stations for progressively shaping the tube so that the preformed opening becomes a larger circular opening defined by outwardly projecting arcuate flanges, then an elongated opening formed by spreading said arcuate flanges,

and finally a still larger circular opening, each of said forming devices including a forming punch, means for actuating said punches toward and away from the tubes, apparatus operable either to effect rotation of the punch at the last operating station while said punch is entered within the tube or to effect movement of the conveyor while said punches are withdrawn from the tube, and a controller rendered effective by the entry of the rotatable punch within the tube for causing the apparatus to perform the first mentioned function and rendered effective by the retraction of the rotatable punch from the tube for causing said apparatus to perform the second mentioned function.

8. In a machine for progressively enlarging an opening in the side of a tube, the combination comprising, a workholder for supporting a tube having a previously formed opening of substantially elliptical shape, a forming punch for entering the opening, said punch being rotatable to form the tube so as to provide an opening of circular shape, means for axially moving the punch into and out of the tube, a rotary shaft supporting the punch, a pinion connected with the shaft, a gear meshing with the pinion, means for moving the gear in either direction, and a controller for the gear moving means conditioned in response to the positioning of the punch within the tube for causing the gear to be moved in one direction and conditioned in response to the positioning of the punch outside the tube for

causing the gear to be moved in the opposite direction, and conveyor moving means operated by movement of the gear in said opposite direction.

- 5 9. In a machine for progressively enlarging an opening in the side of a tube, the combination comprising, a workholder for supporting a tube having a previously formed opening of substantially elliptical shape, a forming punch for entering the opening, said punch being rotatable to form the tube so as to provide an opening of circular shape, means for axially moving the punch into and out of the tube, a rotary shaft supporting the punch, a pinion connected with 10 the shaft, a gear meshing with the pinion, means for moving the gear in either direction, a one-way motion-transmitting mechanism including ratchet and pawl members for moving the conveyor, means connecting one of said members 15 with the gear and a controller for the gear moving means conditioned in response to the positioning of the punch within the tube for causing the gear to be moved in such direction that the ratchet and pawl members are operatively disconnected and conditioned in response to the positioning of the punch outside the tube 20 for causing the gear to be moved in such direction that the ratchet and pawl members are operatively connected.
